UNITED STATES PATENT OFFICE.

WILLOUGHBY S. MILLER, OF READING, PENNSYLVANIA, ASSIGNOR OF ONE-HALF TO
JAMES H. KNOLL, OF READING, PENNSYLVANIA.

DAMPER.

1,105,366.

Specification of Letters Patent. Patented July 28, 1914.

Application filed June 7, 1913. Serial No. 772,401.

To all whom it may concern:

Be it known that I, WILLOUGHBY S. MILLER, a citizen of the United States, residing at Reading, in the county of Berks and State of Pennsylvania, have invented a new and useful Damper, of which the following is a specification.

My invention relates to new and useful improvements in a damper and has for its 10 primary object the provision of means for easily adjusting and regulating the damper to provide the proper draft.

A further object of the invention is the provision of means for adjusting the damper 15 to accommodate stove pipes of various sizes.

With the foregoing and other objects in view which will appear as the description proceeds, the invention resides in the combination and arrangement of parts and in 20 the details of construction hereinafter described and claimed, it being understood that changes in the precise embodiment of the invention herein disclosed can be made within the scope of what is claimed without departing from the spirit of the invention.

In the drawings: Figure 1 is a front view partly broken away to show the interior. Fig. 2 is a view in side elevation; and Fig. 3 is a transverse sectional view on the line 30 A—A of Fig. 1.

In carrying out my invention I provide a cylinder which is formed in two sections 1 and 2 and each of these sections has an opening in the side thereof as indicated at 3. 35 Slots 4, as indicated in dotted lines, Fig. 2, are formed in the edges of each of the sections 1 and 2 and plates 5 are adapted to overlap the meeting edges of the two sections. Threaded bolts 6 extend through the 40 plates 5 and slots 4 and thumb nuts 7 are adapted to be screwed onto the threaded ends of the bolts. By this arrangement the cylinder may be expanded to fit pipes of various sizes.

45 Formed on each side of the openings 3 are the guides 8 in which operate the sliding doors 9 which are provided with the flange 10 at the top to limit the downward movement of the doors. Rods 11 are pivotally connected to the doors at 12 and these rods are provided on the lower ends with the 50 openings 13 which are adapted to receive the projections 14 formed on the sections of the cylinder. Handles 15 are provided on the 55 lower end of each of the rods 7.

A plate 16 is pivotally mounted within the cylinder and as clearly shown in Fig. 3 is of slightly less diameter than the cylinder. This plate 16 is pivoted by means of the rods 17 which enter openings formed in 60 the sections of the cylinder. On the end of one of these rods 17 is secured a crank arm 18 which is also attached to one of the rods 11.

It will be seen that by grasping the handles 15 on the rods 11 the rods may be disengaged from the projections 15 formed on the cylinder and the sliding doors can then be regulated. It will be seen that when operating the sliding door to which the arm 70 18 is connected the plate within the damper will be turned in various positions thereby cutting off the draft through the pipe. By this arrangement I am enabled to secure the proper draft through the pipe at all times. 75 It will also be noted that by this construction the two sliding doors are independently operated and one of the doors may be opened or closed without in any way affecting the position of the plate 16 within the cylinder. 80 It will also readily be apparent that by having the cylinder formed in the two sections it can be adjusted to receive the ends of stove pipes of various sizes. The plates 5 will close the meeting edges of the sections 85 to prevent smoke escaping therefrom. If desired the edges of the sections 1 and 2 could overlap thereby doing away with the plate 5. With this form the bolts would pass through the overlapping edges and 90 only two bolts would be necessary on each side.

Having fully described the invention what I claim as new and desire to secure by Letters Patent is:

1. A damper comprising a cylinder formed in two sections and having an opening in the side of each section, plates covering the meeting edges of the sections, sliding doors for covering the openings in the sections, rods pivotally connected to the doors and having openings therein, projections secured to the cylinder and engaging the openings in the rods, a plate pivotally mounted within the cylinder, and means connecting the plate with one of the door rods. 100

2. A damper comprising an expandible cylinder formed in two sections, each section having an opening in the side thereof and slots in the adjacent edges, plates covering 110

the meeting edges, bolts carried by the plates and entering the slots, sliding doors for covering the openings in the sections, vertically swinging rods connected to the doors and having perforations therein, one of said rods having a perforated projection formed on the side thereof, projections on the sections for entering the perforations in the rods, and a plate pivotally mounted in the cylinder and having a crank arm connected

thereto, the end of said crank arm passing through the perforation in the projection on one of the rods.

In testimony that I claim the foregoing as my own, I have hereto affixed my signature in the presence of two witnesses.

WILLOUGHBY S. MILLER.
